UNITED STATES PATENT OFFICE.

WILLIAM R. HAGER, OF CHICAGO, ILLINOIS, ASSIGNOR TO TROY LAUNDRY MACHINERY CO., LTD., OF CHICAGO, ILLINOIS, A CORPORATION OF NEW YORK.

CURTAIN-STRETCHER.

Specification of Letters Patent.

Patented Mar. 8, 1921.

1,371,025.

Application filed September 12, 1919. Serial No. 323,285.

To all whom it may concern:

Be it known that I, WILLIAM R. HAGER, a citizen of the United States, residing at Chicago, in the county of Cook and State of Illinois, have invented certain new and useful Improvements in Curtain-Stretchers, of which the following is a specification.

This invention relates to a frame, the members of which are adapted to receive and hold the edges of a curtain or other like fabric, and made adjustable in order that the fabric may be put under tension and caused to dry straight and at substantially the dimensions which it is required to have in serving the uses for which it is intended.

One object of the invention is to provide a frame having a holding bar and a stretching bar, and means whereby the holding bar may be given either of two holding positions, whereby the frame may be given either a wide or a narrow initial width in order to adapt it for use in stretching wide or narrow pieces of fabric, a collateral object being to provide a scale for each initial adjustment so that the width to which the work-piece is stretched may be readily read off during the operation of stretching from either initial adjustment; these scales being preferably arranged so that the one not in use is retired from view, at least to the extent of leaving only the other scale associated with the bar that moves in developing the stretching.

Another object of the invention is to provide the shiftable holding bar and the adjustable stretching bar with automatic locking devices that hold them in the positions to which they are moved, and combining with the stretching bar and its said holding means, controlling connections which insure equal movement in the opposite ends of the stretching bar and, therefore, maintenance of parallelism before the stretching bar and the holding bar; the locking means for the bars being preferably in the form of a traveler fitted snugly upon the running rod and traveling freely thereon so long as it maintains a position perpendicular thereto, but automatically biting into or gripping upon the rod under any slight angular displacement thereon such as is imparted by the tension of the goods being stretched, and which it is intended to resist.

The invention will be fully understood

upon reference to the accompanying drawings, in which—

Figure 1 is a plan view of a curtain stretching and drying apparatus to which the several features of the present invention are applied.

Fig. 2 is a side elevation of the same with a portion of the drying box and the frame in section.

Figs. 3 and 4 are detail views on an enlarged scale showing one form of shifting scale in the two different positions which it assumes, and Fig. 4^a is a sectional view of the same on a still larger scale.

Figs. 5 and 6 are detail views of another form of scale device, and Fig. 6^a is a sectional view of the same on an enlarged scale.

Figs. 7 and 8 are detail views of the clutch; and

Fig. 9 is a detail view of the material with which the holding and stretching bars are faced to adapt them to engage the fabric.

Referring to Figs. 1 and 2, A represents a drying box, B the carrying frame supported therein on trunnions C so as to be reversible therein, and D, E, F, G, H, and I represent the members of the curtain stretching frame, which are duplicated on opposite sides of the sheet metal diaphragm Z, or horizontal plane of the trunnions C in the frame B, so that one stretching frame with the fabric stretched thereon may, by rotating the frame B, be presented downwardly to the hot air in the drying box A while the other frame is presented upwardly for removal of a previously dried fabric and the application of another thereon.

The bar D is a fixed bar and is used for anchoring one end of the fabric while it is being stretched lengthwise. The rods E, E' are of such form that one or both of them may be threaded through the fabric in order to hold the same while permitting it to stretch sidewise; said rods E, E' being held at any adjustment to which they may be moved by inserting their ends in the sockets e on the opposite longitudinal sides of the frame B, springs e' at one end of each rod being provided for holding the bars against longitudinal displacement while permitting them to be readily displaced and shifted at will.

The bar F constitutes the holding bar or

stationary anchorage for one side of the fabric, and bar I is the adjustable bar for stretching the fabric sidewise. As thus far described, the elements which enter into the present invention may follow known constructions.

It frequently happens that fabrics to be stretched and dried, for instance, curtains or the like, are too narrow to be conveniently manipulated by a frame constructed primarily for handling wide work-pieces, and accordingly one of the bars, for instance the bar F, is made adjustable laterally to give it different holding positions so that the frame 10 can be presented with an initial width that will hold the work-piece within reach of the stretching bar. But such shifting of the anchoring bar F renders useless the scale in connection with which the bars are used. 15 The present invention overcomes this difficulty by providing for two definite positions of the bar F, namely, that in which it is suitable for stretching wide work, and that which adapts it for use on narrow work; and two separate scales are employed, one of 20 which has reference to its initial position selected for wide work, and the other for the initial position selected for narrow, means being also provided for retiring the scale, 25 or the part thereof which is not appropriate to the work being done at that particular time. Thus, the shiftable anchoring bar F is mounted upon a pair of slide tongues G fitted in channel-beams H so that the anchoring bar F may assume either the position shown in full lines in Fig. 1, or the position shown in dotted lines therein, the tongues G being preferably of a length that will cause them to abut against the opposite side 30 of the frame when the anchoring bar F is in its narrow work position, and so sustain the anchoring bar against the tension of the goods. In either of these positions bar F is adapted to coöperate with the stretching 35 bar I to put proper tension upon the goods and draw them to the lateral dimension required before subjecting them to the hot air or other drying influence.

In order to determine the distance to 40 which the stretching bar I is drawn away from the bar F, and therefore the width that is to be developed in the goods when dried, a scale K is provided on some convenient transverse part, preferably upon the 45 exposed face of one of the confining walls of the channel-beam H, as shown in Figs. 3 and 4, and this scale, expressed in inches or other units of measurement, is definitely related to the more remote anchoring position 50 of the bar F. In order that the adjustment of the stretching bar I may be similarly read off when the anchoring bar F assumes the dotted line position, another scale K' may be provided, for instance, on the exposed 55 face of the other confining wall of the chan-

nel member H, and this scale will be related to the shifted position of the bar F. Then, in order to retire from view the particular scale not in use, a cover plate L of a width sufficient to cover the channel-beam H, excepting the exposed face of one of its confining walls, will be held by strap L' upon the channel-beam H, in a manner to slide laterally thereon, and provided with a slot M that receives a pin O in the sliding 70 tongue G, and which is constructed with such inclination that the traverse of its length by the pin O will shift the cover plate L from side to side. Thus, when the anchoring bar F is withdrawn to the full line position of Fig. 1, the scale K will be exposed to view; and when the bar F is reversed to the dotted line position of Fig. 1 the scale K' 75 will be exposed to view.

If preferred, the scales may be arranged 80 as disclosed in Figs. 5 and 6, according to which scale K², employed for the narrow work anchoring position of the bar F, may be made to constitute part of the scale employed in the wide work portion of bar F 85 by connecting bar F to the outer member H', and having an additional scale K³ on the inner member G' of a transverse telescoping structure, member G' being connected to the opposite side of the frame B. Withdrawal 90 of bar F to its wide work position automatically exposes the scale K³ (see Fig. 6); while adjustment of bar F to the position of Fig. 5, corresponding to the dotted line 95 position of Fig. 1, would retire the scale K³ 100 from view.

In order to secure the fabric throughout a relatively wide marginal portion and upon a plurality of resilient securing pins, the several anchoring and stretching bars are 105 faced with a relatively wide group of small pins P. These are preferably deflected oppositely to the direction of tension developed in the fabric, so that the fabric may be readily drawn over them to establish initial 110 tension, and when pressed down upon them and released, will be automatically held thereon. A material readily obtainable and serving with especial advantage for this purpose is card clothing, such as is used in 115 carding wool or other fibrous material.

To enforce equal movement in opposite ends of the stretching bar I, it is provided with bearings Q, Q', through which it slides on parallel rods Q', Q', and connected on one 120 side of its middle point, for instance, at point R, with a tape S traveling over sheaves T, and on the other side of its middle point, as, for instance, at point R', with a tape S' traveling over sheaves T', and also over 125 the sheaves T and presenting a portion of its length parallel with that portion of the tape S which lies opposite the point of attachment R on the stretching bar I; so that the connection of the two tapes, as at the 130

point V, will insure equal and simultaneous movements at points R and R' in the same direction, and therefore maintain equal distance of the two ends of bar I from the 5 bar F.

In order to maintain bar I in any position to which it is adjusted, it is provided with a clutch W slidable upon and having a pair of jaws W² spread apart by springs W³ 10 and normally gripping transverse rod X, but adapted to be released by the abutments W⁴ of handle W'; the arrangement being such that so long as handle W' is left free, the clutch W will hold the bar I against 15 movement; but by pushing the handle W' in the direction in which it is desired to move the stretching bar, the clutch W will be released and caused to slide freely upon the rod X.

20 Slide shoes Y upon the ends of the bars F and I sustain said ends against depression. These slide shoes may travel upon the metal diaphragm Z which lies in the medial horizontal plane of the carrying frame B.

25 I claim:

1. In a curtain stretcher, a holding bar, and an adjustable stretching bar; the holding bar having two permanently fixed abutments between which the holding bar may 30 slide in taking up either of two holding positions whereby it is adapted for wide work and narrow work; said stretching bar being provided with two measuring scales related, respectively, to the two holding 35 positions of the holding bar.

2. In a curtain stretcher, a holding bar, and an adjustable stretching bar; the holding bar having two permanently fixed abutments between which the holding bar may 40 slide in taking up either of two holding positions whereby it is adapted for wide work and narrow work; said stretching bar being also provided with measuring scales related, respectively, to the two holding positions 45 of the holding bar, means being provided for retiring one of said scales when the holding bar is in position inappropriate thereto.

3. In a curtain stretcher, a holding bar, and an adjustable stretching bar; the holding bar having two permanently fixed abutments between which the holding bar may 50 slide in taking up either of two holding positions whereby it is adapted for wide work and narrow work; said stretching bar being also provided with measuring scales related, respectively, to the two holding positions of the holding bar; means being provided for retiring one of said scales when the holding bar is in position inappropriate thereto; said last-named means comprising a sliding cover member having connections through which it is actuated by the shifting of the holding bar.

4. In a curtain stretcher, a holding bar, and an adjustable stretching bar; the hold-

ing bar having two permanently fixed abutments between which the holding bar may slide in taking up either of two holding positions whereby it is adapted for wide work and narrow work; said stretching bar 70 being also provided with measuring scales related, respectively, to the two holding positions of the holding bar; means being provided for retiring one of said scales when the holding bar is in position inappropriate thereto; said scales being arranged in parallel positions; and said last-named means comprising a laterally sliding cover having connections through which it moves to obscure each scale as the holding bar 75 moves to the position inappropriate to such scale.

5. In a curtain stretcher, the combination of a holding bar adapted to assume a plurality of holding positions, a stretching 85 bar adapted to coöperate with the holding bar when the latter is in any one of its several holding positions, measuring scales appropriate to the several holding positions of the holding bar and adapted to indicate 90 the spacing of the bars with reference to the respective holding positions of the holding bar, a sliding member moving with the holding bar as the latter changes its position, and an obscuring shield coacting with said 95 sliding member to expose or obscure a scale as the holding bar moves to or retires from a holding position appropriate thereto.

6. In a curtain stretcher, the combination of a holding bar adapted to assume a plurality of holding positions, a stretching bar adapted to coöperate with the holding bar when the latter is in any one of its several holding positions, measuring scales appropriate to the several holding positions of the holding bar and adapted to indicate the spacing of the bars with reference to the respective holding positions of the holding bar, a sliding member moving with the holding bar as the latter changes its position, and an obscuring shield coacting with said sliding member to expose or obscure a scale as the holding bar moves to or retires from a holding position appropriate thereto; said 100 shield having a movement transverse to the movement of the sliding member, and having slot and pin connection with said member whereby it receives movement therefrom.

7. In a curtain stretcher, the combination of holding and stretching bars, of which the holding bar has a plurality of holding positions which adapt it for relatively wide and narrow work, a slide carried by said holding bar, a channel guide in which said slide works and along which the stretching bar is 110 adjusted, independent scales arranged along the respective walls of the channel guide and indicating respectively the spacing of the bars relative to the different holding positions of the holding bar, a shield sliding 115

125

130

upon said channel guide to and from positions in which it obscures or exposes the respective scales, and a connection between the sliding member and said shield through which the latter is moved to its respective positions.

8. In a curtain stretcher, holding means, a stretching bar coacting therewith to stretch the work between them, means for holding

10 the stretching bar to its adjustment comprising a rod over which the stretching bar travels, and an automatically engaging clutch carried by the stretching bar adapted to grip said rod.

15 9. In a curtain stretcher, holding means, a stretching bar coacting therewith to stretch the work between them, means for holding the stretching bar to its adjustment comprising a rod over which the stretching bar

20 travels, and an automatically engaging clutch carried by the stretching bar adapted to grip said rod; said clutch having a controlling handle which releases the clutch by pressure in the direction of movement to be imparted to the bar.

25 10. In a curtain stretcher, the combination of holding means, a stretching bar, and means for enforcing uniform movement throughout the length of the stretching bar comprising traveling belts connected with the stretching bar at two spaced points thereon, and having an interconnection one with

the other which insures identical movement of the parts thereof at their points of connection with the bar.

35 11. In a curtain stretcher, the combination of holding means, an adjustable stretching bar, an endless belt guided for travel through the portion of its length running with the stretching bar and secured thereto to control the movement of the bar, and a second endless belt having one portion of its length running with the stretching bar and attached thereto at a point remote from the point of attachment of the belt first named 40 and having another portion of its length attached to and driven by the portion of the belt first named which runs oppositely to the bar.

45 12. In a curtain stretcher, holding means, a stretching bar, guiding sheaves spaced apart in the direction of the length of the bar and also in the direction of its adjusting movements, and a pair of endless belts each having a portion moving with the bar and a portion moving oppositely thereto and having their portions which move with the bar connected to the bar at spaced points on the latter, and having their portions which run oppositely to the bar united together to insure identical movements in the belts.

50 Signed at Chicago, Illinois, this September 3, 1919.

55 WILLIAM R. HAGER.
